UNITED STATES PATENT OFFICE.

HUGO SONTAG, OF ST. LOUIS, MISSOURI.

IMPROVEMENT IN EXPANDING ROCK-DRILLS FOR SHAFT-BORING APPARATUS.

Specification forming part of Letters Patent No. 134,943, dated January 14, 1873.

To all whom it may concern:

Be it known that I, HUGO SONTAG, of the city and county of St. Louis and State of Missouri, have invented certain Improvements in Expanding Rock-Drills for Shaft-Boring Apparatus, of which the following is a specification:

My invention consists in the employment of a bit sliding horizontally in combination with a spring, the motion of which is limited by a set-screw, by means of which the sliding bit is forced out by the spring, and allowed also a backward movement to prevent any possibility of jamming.

Figure 1 is a side view of the bit, showing the spring-bit in its retracted position. Fig. 2 is a side view, showing the spring-bit in its forward position. Fig. 3 is an inside and Fig. 4 an outside view of the bit. Fig. 5 is a section at the line *x x*, Fig. 1.

Fig. 1 is a drill-bit similar to that shown in my application for patent on or about the 15th day of January, 1872, except that with the said bit K is associated a horizontally-sliding bit, L, arranged to cut the outer circumference of the enlarged bore. This spring-bit has a

downwardly-curved end or cutter, M, and a shank, N, sliding in suitable guide-grooves of the bit K. The two parts of the shank are connected by a cross-bar, O, against which bears a spring, P, in such manner as to force the bit outward, but yet to allow its inward movement to prevent its becoming jammed fast against the side of the shaft-bore. R is a set-screw by which the outward movement of the radially-sliding bit L is limited. This bit may have a play of one inch, more or less, according to the character of the earth or rock through which the shaft is being sunk.

Claim.

I claim as my invention—

The combination of the horizontally-sliding bit L, cross-bar O, spring P, and set-screw R, constructed and operated as and for the purpose set forth.

In testimony of which invention I have hereunto set my hand.

HUGO SONTAG.
